UNITED STATES PATENT OFFICE

153,335

DESIGN FOR A JUVENILE PLAY YARD

Irving Brand, Brooklyn, N. Y., assignor to Calvin Corporation, Long Island City, N. Y., a corporation of New Jersey

Application April 10, 1947, Serial No. 138,278

Term of patent 14 years

(Cl. D5—5)

To all whom it may concern:

Be it known that I, Irving Brand, a citizen of United States and a resident of the Borough of Brooklyn, in the city of New York, the county of Kings, and the State of New York, have invented a new, original, and ornamental Design for a Juvenile Play Yard, of which the following is the specification, reference being had to the accompanying drawing, forming part thereof.

The figure shown in the drawing is a perspective view of a juvenile play yard, showing my new design.

The reverse side of this play yard is a substantial duplicate of that shown in the drawing.

I claim:

The ornamental design for a juvenile play yard, substantially as shown and described.

IRVING BRAND.
